UNITED STATES PATENT OFFICE.

CHARLES A. HAMMEL, OF LOS ANGELES, CALIFORNIA.

OIL-BURNING STEAM-BOILER.

No. 882,756.

Specification of Letters Patent. Patented March 24, 1908.

Application filed February 4, 1907. Serial No. 355,595.

To all whom it may concern:

Be it known that I, CHARLES A. HAMMEL, a citizen of the United States, residing at Los Angeles, in the county of Los Angeles and State of California, have invented new and useful Improvements in Oil-Burning Steam-Boilers, of which the following is a specification.

The object of my invention is to provide means for effectively and economically generating steam in boilers of locomotives, marine, stationary and other types by the combustion of liquid hydrocarbons, such means being designed to attain complete combustion of the fuel within the fire box, and the application of the evolved heat to the entire heating surface of the fire box without injury to the fire box sheets or inducing leaky flues, thereby avoiding the objections heretofore encountered in leaky steam pipes and tubes in front end.

A further and special object of my invention is to prevent the entrance of an excessive amount of cold air to the fire box.

Another object of my invention is to provide a plurality of burners arranged so as to neutralize the force of the burners, whereby the heat is more evenly and uniformly distributed to the combustion chamber and boiler.

A further object is to provide novel means for the retardation and uniform distribution of the main air supply to the combustion chamber.

Another object is to provide an oil burning furnace that is economical in operation and in which the heat units evolved therefrom are fully utilized.

I accomplish these objects by means of the device described herein and illustrated in the accompanying drawings, in which:

Figure 1 is a vertical longitudinal central section through the fire box and adjoining portion of the waist of a steam boiler, illustrating an application of my invention. Fig. 2 is a vertical transverse section taken on line 2—2 of Fig. 1 looking in the direction of the arrows. Fig. 3 is an enlarged fragmental sectional plan view of the bottom of the combustion chamber taken on line 3—3 of Fig. 2 looking in the direction of the arrows.

As will be observed my invention is illustrated as applied to an ordinary type of locomotive boiler, but as will be noted is not limited in application to this or any other special type or form of boiler, it being adapt-

ed to use in any of the various constructions which are provided with a fire box or furnace and tubes leading therefrom.

Referring to the drawings the inside fire box or combustion chamber 5 is of the usual type and is closed at its top by a crown sheet 6 and surrounded by water jackets 7, the bottoms of which are closed by the usual mud ring 8. The outside shell 9 of the fire box is connected to the waist 10, through which the tubes 11 pass from the tube sheet 12 to the smoke stack (not shown) at the front end of the boiler.

The fire box 5 is closed at the bottom by a sheet or plate metal box 13 which corresponds in general form to the ash pan of locomotive boiler in which fuel of a solid type is used.

Box 5 is provided with a metallic bottom plate 14 which has a rectangular opening that is closed by a plate 18 bolted or otherwise secured to plate 14. Plate 18 is provided with a plurality of air inlet openings 15, preferably arranged in staggered relation as shown in Fig. 3 of the drawings, and rigidly secured in these openings are a plurality of short metal tubes 16 whose upper ends are flush with the top of fire brick 17 with which the box 13 is preferably lined. The space around the tubes above plate 18 is preferably filled with a heat resisting material 17'. Secured to plate 14 and directly below the tubes 16 is a metal shield 19 open at its sides for the admission of air through the tubes into the fire box. This shield is provided with a centrally disposed longitudinal partition or plate 20. This partition is for the purpose of equally distributing the volume of air through the inlets 15 to the combustion chamber 5.

The leading and characteristic feature of admitting air to the combustion chamber forms with the novel placement of the burners (which will be more particularly described hereinafter) one of the most important and essential features of my invention, in that the method of taking the main air supply from the bottom through a series of tubes prevents an entrance of an excessive or undue amount of cold air to the combustion chamber, and at the same time retards the volume of air entering thereto and enables me to effect a more uniform distribution. Also as the tubes become heated from the operation of the burners, the air as it enters becomes expanded and heated to a high temperature so that it will readily form a union

with the gases that are being consumed by the burners.

At the front and rear end of box 13 are transversely disposed fire brick arches 21 and 22, and centrally located beneath each arch is a hydrocarbon burner, 23 and 24 of the usual type of construction, which project through air inlets 25 and 26 formed in the front and rear walls of the box 13. The placement of these burners forms as equally important a function as the air supply. The disposition of the burners so that their flames will be directed toward each other tends to neutralize all the ill effects that arise from the operation of a single burner, such as damage to the interior construction and the exposure of the flues, crown, side and back sheets to an excessive amount of heat, thus causing the flues to leak and the sheets to become warped and damaged to such an extent as to render their removal obligatory in a short time. The burners are connected to a source of supply (not shown) and are directly under the control of the fireman in the engine cab.

In the operation of my improved furnace the flames from the oppositely disposed burners are delivered toward each other and meet approximately in the center of the lower portion of the combustion chamber and directly over the air inlet openings 15 formed by the tubes in the bottom plate 18, where they are met by the incoming air, which tends to raise the flames and prevent dragging. The natural draft of the engine through the tubes and smoke stack tends to carry and distribute the heat uniformly to all parts of the combustion chamber and flues.

The novel arrangement of the arches prevents an undue entrance of an excessive amount of cold air through the air inlets 25 and 26 and at the same time prevents the natural draft of the engine from drawing the flames of the burners upwardly which would tend to nullify their effectiveness.

It will be observed from the foregoing description that I have produced an entirely novel form of hydrocarbon burning furnace and one in which economy of operation and the conservation of heat units are attained,

Having described my invention what I claim as new and desire to secure by Letters Patent is:

1. The combination, with a steam boiler,

of a fire box having a refractory lining on the bottom and sides; of oppositely disposed hydrocarbon burners located at the front and rear end of the fire box adapted to discharge their flames toward each other; means for establishing a draft of air into the fire box adjacent the burners; deflector means extending into the fire box and located above said burners; a plurality of air inlets in the bottom of said fire box adjacent to and under the meeting point of the flames; and means located beneath the air inlets in the bottom of the fire box for equally distributing the volume of air to the inlets.

2. The combination, with a steam boiler of a fire box having a refractory lining on the bottom and sides; of oppositely disposed hydrocarbon burners located at the front and rear ends of the fire box, adapted to discharge their flames toward each other; means for establishing a draft of air into the fire box adjacent the burners; deflecting arches of refractory material extending into the fire box and located above said burners; a plurality of air inlets in the bottom of said fire box adjacent to and under the meeting point of the flames, said air inlets comprising a series of metallic tubes held in place by a refractory material; a horizontally disposed metallic shield secured to the bottom plate of said fire box beneath said air inlets; and a centrally disposed vertical partition secured to the upper face of said shield, whereby the volume of air to the inlet tubes is equally distributed.

3. The combination with a steam boiler having a fire box, of means for delivering hydrocarbon flames from the front and rear of the fire box toward each other into the fire box, means for establishing a draft of air into the fire box adjacent the flame delivery means, means for admitting air directly into the fire box adjacent to and under the meeting point of the flames, and means located beneath said air admission means for equally distributing the volume of air to said admission means.

In witness that I claim the foregoing I have hereunto subscribed my name this 24th day of January, 1907.

CHARLES A. HAMMEL.
